AND ONE-THIRD TO MORRIS WACHTEL, BOTH OF NEW YORK, N. Y.

RAILROAD TIE

Application filed February 5, 1929. Serial No. 337,541.

The present invention relates to railroad ties and more particularly to sectional ties and method of making.

A substantial part, if not all, of the railroads in this country have rails laid upon wooden ties, the ties being approximately eight feet long. It is common knowledge that these ties are relatively expensive and that they become more expensive yearly due to the decrease in the available lumber supply. Various types of substitutes have been attempted, such as cement, steel and the like, but for various reasons have been unsuccessful. In some cases, there was not sufficient resilience to provide a smooth roadbed, in other cases the substitutes were too expensive. In addition, the roadbeds have to be inspected constantly to determine the worn or burned ties no longer useful and these have to be replaced. These replacements and inspections increase substantially the upkeep of the roadbeds for railroads.

The present invention aims to overcome the above difficulties by providing a railroad tie adapted to be manufactured from wood which at the present time is not used and, hence, is of very little value commercially. This decreases the cost of the tie. In addition, the method of manufacture provides a tie having a resilience equal to or greater than that of the present types of ties and adapted to wear longer without repairs or replacements.

An object of the present invention is to provide an inexpensive railroad tie adapted to give greater wear and a more perfect roadbed.

Another object of the invention is to provide a method of making railroad ties from wood which would otherwise be wasted.

Another object of the invention is to provide a sectional tie having the surface of the respective sections heat treated to increase the weather resisting properties thereof.

Other and further objects of the invention will be obvious upon an understanding of the illustrative embodiment about to be described or will be indicated in the appended claims, and various advantages not referred to herein

will occur to one skilled in the art upon employment of the invention in practice.

A preferred embodiment of the invention has been chosen for purposes of illustration and description and is shown in the accompanying drawings, wherein

Fig. 1 is a perspective view of a completed tie;

Fig. 2 is an end view, showing another form of tie;

Fig. 3 is a detailed view of the plates which are adapted to be wrapped around the sections of the tie to hold them in position;

Fig. 4 is a detailed view of a slightly different form of plate adapted to be used at curves and similar places on the roadbed to provide additional support for the rails.

Fig. 5 is a sectional view along line 5—5 of Fig. 4;

Fig. 6 is a fragmentary top plan view of a rail attached to several ties;

Fig. 7 is a diagrammatic view illustrating the application of heat and pressure to the sections of the tie;

Fig. 8 is a detailed illustration of a preferred form of bolt for holding the rail in position; and

Fig. 9 is a detailed sectional view illustrating a preferred form of tie composed of branches from trees with the bark thereon.

In the manufacture of the present type of railroad tie, certain types of trees are cut down and made into proper lengths for the formation of ties. The longitudinal sawing of the trees to make the ties may be done in the vicinity of the place where the trees have stood or the logs may be shipped to some central milling plant for the sawing operation. In either event, there is a considerable waste of material due to the sawing operations and to the loss of the parts of the tree which are not used. Ties are made only from the very best part of the tree, that is, the trunk. The limbs and lap of the tree are permitted to rot in the woods. The present invention contemplates the use of the limbs and the lap of the tree without substantial waste of material.

By making the tie in sections it is possible to utilize any size or shape of lumber and as-

semble it with suitable additional pieces of lumber to form a tie of proper dimensions. Naturally, the limbs of the trees are seldom straight and, hence, sawing of them would be difficult. The present invention contemplates reducing these portions of the tree to the proper size by compressing them to a size substantially less than their former size. In doing this, the shape may be changed to combine with the shapes of the other pieces of lumber forming one or more ties. The compressing operation may be performed with the bark on the limb or after it has been removed. The pressure reduces the bark to a state where its tendency to absorb water is greatly minimized. In addition, the present invention contemplates the application of heat to the external surface of the various sections, to harden the surface and to render it resistant to weather conditions, thereby eliminating the use of chemicals for this purpose. While the above method has inherent advantageous characteristics other than those described herein, nevertheless the illustrated embodiment is peculiarly adapted to the above method.

Referring more particularly to the drawings, there is shown in Fig. 1 a railroad tie having a plurality of sections 1 of such size and number as to form a railroad tie of proper size. In Fig. 1 the number of sections is shown as six, whereas in Fig. 2 a slightly different form of tie shows four sections. The sections shown in each of these figures may be made from branches of trees or the like. While the various sections can, of course, be secured together in any suitable manner, the preferred embodiment, illustrated in Fig. 3, is a strap or metallic blank 3 having a central part 4 adapted to fit on the upper side of the tie with a pair of apertures 5 therein adapted to receive suitable bolts or spikes 6 for securing the rail in position. The ends of the blank extend from diagonally opposite sides of the central part and are adapted to be bent downwardly around a section of the tie, as shown in Fig. 1. Preferably, the members 7 are of sufficient length to permit them to extend down one side and over the bottom of the tie, with the free end bent upwardly over a part of the outer side of the tie, as shown at 9. Suitable apertures 10 may be formed in the members 7 to permit nails or spikes to be driven therethrough to secure the various sections of the tie rigidly in position.

In Figure 4, a blank differing slightly from that in Fig. 3 is shown. This blank is provided with a strip of metal 12 punched from the central part of the blank and bent upwardly to fit into the side of a rail 11. Such a blank is particularly useful on bends and curves in the roadbed. By using such a blank, the rail may be inserted in the side of the upwardly bent part 12 and the in-

wardly extending portions will fit into the side of the rail to brace the rail against slipping and also against turning over under the pressure exerted by the train moving thereover. The various sections of the tie give greater resilience than a one piece tie affords. This gives a smoother roadbed and permits the compression of the sections into the proper shape without increasing the rigidity of the tie materially.

A diagrammatic construction is shown in Fig. 7 for shaping and heat treating the respective sections. While any type of apparatus may be used for this purpose, there is shown in the drawing a combined bed and side plate 14 wherein is placed the material 17 to be compressed into sections. A movable horizontal compressing member 15, together with a movable vertical compressing member 16 compresses the section into the desired form. Any suitable heating means such as superheated steam or gas jets (not shown) may be used for furnishing heat to the bed plate and compressing members for the purpose of heat treating the outer surface of the sections during the compressing process. The sections may be compressed individually or in groups, as desired.

Preferably, the respective sections are placed in suitable holders after the shaping operation and the blanks 3 are fitted thereabout and secured thereto to hold them firmly in position. However, it will be understood that the sections or branches may be first assembled, and thereafter reduced to the proper size by applying pressure to the group. There is no necessity for all of the sections being alike and, hence, limbs or pieces of lumber of various sizes may be made into different sized sections, several of which are adapted to complete a tie.

While any suitable means may be utilized for securing the rail to the tie, a preferred form of bolt 20 is shown in Fig. 8. This bolt is sufficiently long to extend through the tie. The upper end is provided with relatively large threads 21 adapted to receive a nut 22 serrated at its bottom 24 for engagement with the base of the rail. A projection 25 extends from the end of the bolt substantially smaller than the bolt to receive a lock nut 26 recessed and serrated at its bottom, as shown at 27 and 28 respectively, and threaded to the smaller threads 29. By means of the nut 22 a very secure grip is obtained on the rail and by means of the nut 26 and the smaller threads 29, a secure lock is attained which prevents the nut 22 from becoming loose.

In Fig. 9, there is shown a sectional view of a tie formed of branches 30 of trees which have been compressed substantially to their proper shape without removal of the bark. It will be understood that the sections can be compressed until they are square but, as shown, the sections are substantially square,

the corners being slightly rounded. By forming the sections in this manner, less compression is required to shape them and the compressive forces may be smaller.

It will be seen that the present invention provides a construction which may be readily manufactured from waste material, thereby decreasing its cost. The resulting tie has excellent wearing properties and inherent resilience adapted to provide a smooth roadbed requiring less inspection and less replacement of ties. Further, the ties may be utilized in present types of roadbeds without necessitating changes therein. By utilizing the present method a substantial saving may be made.

As various changes may be made in the above embodiment without departing from the spirit of the invention, it is to be understood that all matter herein is to be interpreted as illustrative and not in a limiting sense.

Having thus described my invention, I claim:

1. A railroad tie comprising the combination of a plurality of sectional members formed from the branches of trees and shaped to fit together to compose a railroad tie, and a band of metal adapted to be wrapped about said sectional members to hold them in place and to furnish means for securing a rail to the tie.

2. A railroad tie comprising the combination of a plurality of sectional members compressed into shape to fit together and to form a tie, and means for securing said members together, said means being adapted to fit under a rail, and having a part cut and bent out of the plane of said means to fit against the rail to hold it in position.

3. A railroad tie comprising a series of sections, said sections having their exterior surfaces subjected to a relatively high temperature to improve the wear thereof, and means for securing said sections together.

4. A railroad tie comprising the combination of a plurality of sections heat treated to render the exterior surfaces thereof resistant to weather and pressed into the proper shape to combine with other sections in forming a tie.

5. A railroad tie comprising the combination of a plurality of sections, each of said sections being pressed into proper shape to fit with other sections, the external surfaces of said sections being heat treated to increase the wear thereof, and means extending about said sections to hold them in position.

6. A railroad tie formed from wood which has been compressed into the desired shape, and the external surface of which has been heat treated to increase the wear thereof.

7. A railroad tie comprising a plurality of pieces comprising the branches of trees, the cross-sectional dimensions of each branch

being substantially less than the cross-sectional dimensions of the tie.

8. The method of making railroad ties which comprises pressing a plurality of branches from trees into shapes adapted to form a tie, and securing said branches together in their proper relation.

9. The method of making railroad ties which consists in heat treating the external surfaces of the tie to increase the wear thereof.

10. The method of making railroad ties which consists in shaping a series of sections to adapt them to be assembled in proper relation to form a tie, heat treating the external surface of said sections, and securing the sections together in proper relation to form a tie.

11. The method of utilizing the laps and branches of trees in making railroad ties which comprises shaping the tree branches to fit with other branches, assembling said shaped branches and binding said branches together to form a railroad tie.
